UNITED STATES PATENT OFFICE.

ISAAC SCHEUER, OF NEW YORK, N. Y.

DESIGN FOR A POCKETBOOK.

SPECIFICATION forming part of Design No. 22,417, dated May 9, 1893.

Application filed February 11, 1893. Serial No. 461,984. Term of patent 3½ years.

To all whom it may concern.

Be it known that I, ISAAC SCHEUER, of the city, county, and State of New York, have invented a new and original Design for a Pocketbook, of which the following is a specification.

Reference is to be had to the accompanying drawing forming a part of this specification, in which the figure is a perspective view of a pocket book showing my design.

10 The leading feature of the design consists in a box-like figure A arranged on the outer side of a pocket book B. The pocket book B is rectangular in shape and of book form.

The inner sides C and bottom D of the box-like figure A are irregular in contour to give 15 a flexible and loose effect, in sharp contrast to the rigid face of the side of the pocket book B, and the cover-like figure E of the box like figure A.

I claim—

20 The design for a pocket book as herein shown and described.

ISAAC SCHEUER.
